FUEL INJECTION PUMP FOR DIESEL TYPE ENGINES

Paul H. Schweitzer, State College, Pa., assignor to
The Pennsylvania Research Corporation, State
College, Pa., a corporation of Pennsylvania

Application November 9, 1940, Serial No. 365,125

6 Claims. (Cl. 103—41)

This invention relates to port-controlled fuel-injection jerk pumps for internal combustion engines of the Diesel type, and particularly for engines of that type that are used for driving various kinds of vehicles, such as automobiles, trucks, airplanes and the like.

The quantity of fuel injected per cycle by such pumps is usually controlled by a rod, but it is well known that with a fixed setting of the control rod the metering of fuel by a pump increases with increasing speed of the pump, which results in an undesirable smoky exhaust. It also results in unstable engine operation and a tendency to stall because a decrease in engine speed caused by a sudden increase in load resistance produces reduced injection and so further reduces the speed of the vehicle until it stalls. The reason usually ascribed to this increased metering of fuel at increased speed is that the delivery of fuel into the discharge tube leading from a pump occurs earlier and its termination takes place later because of a throttling action in the inlet and by-pass ports of the pump. For maximum torque and to avoid a smoky exhaust and also for engine stability it is desirable, with a fixed setting of the control rod, to deliver a decreasing amount of fuel with increasing speed, which is generally designated as a "declining characteristic" of fuel delivery. While various expedients have been proposed, and some have been used, for effecting a declining characteristic of fuel delivery, they are all objectionable for one reason or another.

The object of my invention is to provide a port-controlled fuel injection pump of the type and for the purpose described with simple and effective means for producing a declining characteristic of fuel delivery, or in other words for decreasing the amount of fuel delivered by each stroke of a pump plunger as the speed increases, the means for this purpose being readily applicable to types of fuel injecting pumps now in use with little or no increase in the cost of their manufacture.

Pumps of the type contemplated by my invention include a barrel which is provided with a port that communicates with a source of fuel supply, and also with a discharge passage adapted to be connected to a discharge tube leading to an engine cylinder. Within the barrel there is a fuel-feeding plunger which may be reciprocated by the usual cam shaft in timed relation with the cycle of the engine. Controlling the discharge passage of the barrel there is a valve which is yieldingly pressed towards closed posi-

tion and whose seat is formed upon a prolongation of the barrel that is usually, although not necessarily, a separate element.

To effect a declining characteristic in the operation of such a pump, I provide its barrel, between its plunger and delivery valve, with a leakage passage for the escape from the barrel of a small amount of fuel, the amount increasing with the increase of pump speed. Preferably the leakage escape passage communicates with the source of fuel supply, as for example with a sump surrounding the barrel. The leakage escape passage is preferably quite shallow to effect or promote laminar flow through it, while the discharge line from the pump is substantially circular in cross section which results in turbulent flow through it. Discharge of fuel from the pump barrel under laminar flow varies as the first power of the pressure of the fuel, while discharge under turbulent flow varies as the square foot of that pressure. Thus, as the pressure of the fuel in the barrel increases consequent upon increased pump speed, more fuel will pass through both the leakage passage and the discharge line, but the increase through the leakage passage is relatively more than through the discharge line because of the above-explained difference between the variations of laminar and turbulent flow due to changes in pressure of the fluid. To further increase the flow of fuel through the leakage passage as the pressure of the fuel in the barrel increases consequent upon increased pump speed, the leakage escape passage may be of variable cross section adapted to increase with increasing fuel pressure.

The flow of fuel through the leakage escape passage may be made more pronounced by restricting the flow of fuel from the barrel into the discharge line. This may be done by providing the pump with a throttling orifice which may be variously located, by limiting the lift of the discharge valve, or by the construction of such valve.

The invention is illustrated in the accompanying drawing of which Fig. 1 is a vertical central sectional view through a port-controlled fuel injection pump; Fig. 2 a similar view through a like pump showing modifications of construction; and Fig. 3 a vertical central sectional view through the delivery valve of the pump showing a further modification of construction.

The pump illustrated in Fig. 1 includes a barrel 1 mounted in a casing or body 2 and provided with a reciprocable plunger 3. On the upper portion of the plunger there is a helix 4 of familiar construction adapted, by being rotated

upon its axis, to control the effective stroke of the plunger by placing the barrel space above the plunger in communication with a spill passage 5. Fuel is supplied to the barrel through spill passage 5 and an inlet port 5a. For thus adjusting the angular position of plunger 3, or in other words for rotating it upon its axis, there is a control rod 6 which is provided with a rack 7 that meshes with a pinion 8 attached to a sleeve 9 which is rotatably mounted upon barrel 1 and engages the lower end of the plunger.

Port 5a and spill passage 5 of the barrel communicate with a sump 11 formed in the pump body and which in turn has communication with a source of fuel supply. At the upper end of barrel 1 there is a delivery valve assembly including a bushing 12, which in effect is a prolongation of barrel 1, having a seat at its upper end for receiving a discharge controlling valve 13 which is yieldingly pressed towards its closed position by a spring 14 seated at its upper end in a valve holder 15 that is attached to pump body 2.

In this embodiment of my invention the pump is provided with a leakage escape passage of variable cross section. To that end, annular spring washers 16, of the Belleville or similar type, are placed between the lower end of valve holder 15 and an outwardly extending flange at the lower end of bushing 12 (the interior wall of which bushing overhangs the wall of barrel 1) and pump body 2 is provided with a channel 17 extending from the space surrounding bushing 12 to sump 11. Depending upon the fuel pressure in the pump barrel, bushing 12 is elevated to form a shallow leakage escape passage 18 of variable cross-sectional area between the lower end of the bushing and the upper end of the barrel.

In the embodiment of my invention illustrated in Fig. 2, a similar shallow leakage escape passage 18a, but of fixed cross-sectional area, is formed between barrel 1 and bushing 12 which are not movable with relation to each other during the operation of the pump.

For throttling the discharge flow of fuel from the pump, and thereby to make the declining delivery characteristic of fuel more pronounced by increasing relatively the laminar flow of fuel that escapes through the leakage passage, delivery valve holder 15 may be provided with a throttling orifice 20, as shown in Fig. 1. As shown in Fig. 2, a similar throttling of the discharge flow of the fuel may be effected by providing valve 13a with a depending skirt 21 which fits loosely within the bore of bushing 12a. The upper portion of skirt 21 is provided with a peripheral groove 22 and with small openings 23 which place the groove in communication with the interior of the skirt. Fuel flows from the pump chamber between the exterior of skirt 21 and the bore of bushing 12a, and also through the interior of that skirt and holes 23, by which restricted passages the discharge flow of fuel is throttled.

The flow of discharge fluid may also be throttled by providing the delivery valve with means for limiting the extent of its opening under fuel pressure. As shown in Fig. 3, this may be accomplished by providing the upper end of bushing 12b with a stop in the form of a ring 25 which threadably engages the upper end of the bushing and is provided with an inwardly turned flange 26 that overhangs the top of valve 13b. The throttling thus produced by limiting the

opening of the valve may be varied by adjusting the position of ring 25.

In the operation of the fuel injection pump provided according to my invention the angular position of the pump plunger is adjusted, as usual, to effect the desired feed of fuel depending upon the engine load. When the engine speed increases, and as a consequence thereof more fuel is supplied to the engine by reason of the increased speed of reciprocation of the pump plunger, a portion of the fuel flows through the leakage escape passage to the source of fuel supply, this portion varying with the increase in speed. In this way the feed of fuel has the desired declining characteristic resulting in increased torque, elimination of or reduction in smoke in the exhaust, and better engine stability.

According to the provisions of the patent states I have explained the principle of my invention and have illustrated and described several embodiments of it. However, I desire to have it understood that, within the scope of the appended claims, the invention may be practiced otherwise than as specifically illustrated and described.

I claim:

1. A port-controlled injection pump for internal combustion engines of the Diesel type, comprising in combination a barrel provided with a port communicating with a source of fuel supply and with a discharge passage, a valve controlling flow of fuel through the discharge passage, and a fuel feeding plunger reciprocable in said barrel, the barrel being provided with a mechanically-controlled spill passage and also with a leakage escape passage having its inlet positioned between said valve and plunger and being in communication with the source of fuel supply, flow of fuel through said leakage escape passage being effected and controlled solely by the pressure applied to the fuel by the pump.

2. A port-controlled injection pump for internal combustion engines of the Diesel type, comprising in combination a barrel provided with a port communicating with a source of fuel supply and with a discharge passage, a valve controlling flow of fuel through the discharge passage, and a fuel feeding plunger reciprocable in said barrel, the barrel being provided with a mechanically-controlled spill passage and also with a shallow leakage escape passage having its inlet between said valve and plunger and being formed to promote laminar flow of fuel from the barrel, flow of fuel through said leakage escape passage being effected and controlled solely by the pressure applied to the fuel by the pump.

3. A port-controlled injection pump for internal combustion engines of the Diesel type, comprising in combination a barrel provided with a port communicating with a source of fuel supply and with a discharge passage, a valve controlling flow of fuel through the discharge passage, and a fuel feeding plunger reciprocable in said barrel, the barrel being provided with a mechanically-controlled spill passage and also with a shallow leakage escape passage of fixed cross-sectional area having its inlet between said valve and plunger and formed to promote laminar flow of fuel from the barrel, flow of fuel through said leakage escape passage being effected and controlled solely by the pressure applied to the fuel by the pump.

4. A port-controlled injection pump for internal combustion engines of the Diesel type,

comprising in combination a barrel provided with a port communicating with a source of fuel supply and with a discharge passage, a valve controlling flow of fuel through the discharge passage, and a fuel feeding plunger reciprocable in said barrel, the barrel being provided with a mechanically-controlled spill passage and also with a shallow leakage escape passage of variable cross-sectional area having its inlet between said valve and plunger and being formed to promote laminar flow of fuel from the barrel, flow of fuel through said leakage escape passage being effected and controlled solely by the pressure applied to the fuel by the pump.

5. A port-controlled injection pump for internal combustion engines of the Diesel type, comprising in combination a barrel provided with a port communicating with a source of fuel supply and with a discharge passage, a valve controlling flow of fuel through the discharge passage, a fuel feeding plunger reciprocable in said

barrel, the barrel being provided with a shallow leakage escape passage having its inlet between said valve and plunger and being formed to promote laminar flow of fuel from the barrel, and means beyond said escape passage for throttling the flow of fuel.

10 6. A port-controlled injection pump for internal combustion engines of the Diesel type, comprising in combination a barrel provided with a port communicating with a source of fuel supply and with a discharge passage, a valve controlling flow of fuel through the discharge passage, a fuel feeding plunger reciprocable in said barrel, the barrel being provided with a shallow leakage escape passage having its inlet between said valve and plunger and being formed to promote laminar flow of fuel from the barrel, and a restricted orifice beyond said escape passage for throttling the flow of fuel.
